UNITED STATES PATENT OFFICE.

RALPH C. ENYART, OF CONNERSVILLE, INDIANA, ASSIGNOR TO THE
P. H. & F. M. ROOTS COMPANY, OF SAME PLACE.

DESIGN FOR A HEAD FOR ROTARY PUMPS.

SPECIFICATION forming part of Design No. 28,491, dated April 19, 1898.

Application filed March 3, 1898. Serial No. 672,463. Term of patent 14 years.

To all whom it may concern:

Be it known that I, RALPH C. ENYART, a citizen of the United States, residing at Connerville, Fayette county, Indiana, have invented and produced a new and original Design for Heads for Rotary Pumps, of which the following is a specification, reference being had to the accompanying drawing, showing the same in perspective.

10 The leading feature of my design consists in a plate having semicircular ends and having projecting from one of its faces a parallel pair of seven-walled boxes open at their tops.

15 In the drawing, A is the plate, having semicircular ends, and B B are the boxes, disposed

parallel with each other and projecting out from one of the surfaces of the plate, each box being open at its top and having seven walls—to wit, four vertical walls in different planes, two horizontal walls in a common plane, and one horizontal wall in an independent lower plane.

What I claim is—

The design for a head for a rotary pump, substantially as shown and described.

RALPH C. ENYART.
